CLAIM

The ornamental design for a children's toy, substantially as shown and described.

DESCRIPTION

FIG. 1 is a top perspective view of a children's toy, according to an example embodiment of the design;

FIG. 2 is a front view of the children's toy of FIG. 1;

FIG. 3 is a rear view of the children's toy of FIG. 1;

FIG. 4 is a right side view of the children's toy of FIG. 1;

FIG. 5 is a left side view of the children's toy of FIG. 1;

FIG. 6 is a top view of the children's toy of FIG. 1; and,

FIG. 7 is a bottom view of the children's toy of FIG. 1.

Portions shown in broken lines are for illustrative purposes only and form no part of the claimed design.
